UNITED STATES PATENT OFFICE

MARTIN JANKISZ, OF BROOKLYN, NEW YORK

HANDTRUCK

Application filed March 11, 1932. Serial No. 598,103.

My invention relates to a handtruck which is particularly adapted for the transportation of heavy objects, especially ashcans, up and down flights of stairs.

More specifically my invention resides in a handtruck which is so constructed as to operate on level surfaces in the same manner as an ordinary handtruck and which is provided with means, normally so arranged as to provide no impediment to the normal operation of the truck, for coacting with the tread of a flight of stairs for lifting or lowering the truck with its load, such means being of a nature to relieve the operator of the labor normally encountered in this operation. This lifting and lowering means can, of course, be so designed as to still further relieve the operator.

The object of my invention is to improve the truck shown in my Patent No. 1,839,317. The nature of these improvements and the further objects and advantages of my invention will appear more fully from the following detailed discussion of the accompanying drawing in which:

Fig. 1 is a front elevation of my device with the lifting means out of operative position;

Fig. 2 is a detail of part of the frame of my device;

Fig. 3 is a plan view of my device in the position shown in Fig. 1;

Fig. 4 is a side elevation of my device at the beginning of the lifting operation; and

Fig. 5 is a side elevation of my device at the end of the lifting operation.

Referring to the drawing in detail 1 represents the frame which is made of a metal rod or tube of any cross sectional shape which is bent to form the nose 2 and cradle 3 of the truck. This bending is done in such a way as to leave one of the free ends of the rod or tube longer than the other. At the upper end of the cradle the free ends of the rod or tube are arranged in juxtaposition to each other, the long free end being bent to form a handle 4. The free ends meet below said handle and overlap in such a manner that either of them can be turned up to form a stud 5 (shown in Fig. 2 as the upper free

end). At a predetermined point along the handle there is provided a clamp 6 which is adapted to grasp the upper end of an ashcan. Fulcrumed on the stud 5 is a lever 7 which is divided by the fulcrum into a long arm and a short arm. Pivot to the end of the short arm, preferably by a universal joint, is a lifting rod 8. A spring 9 has one of its ends attached to a predetermined point on the lifting rod 8, and the other of its ends attached to the cradle of the truck near the axle 10. It may be pointed out here that instead of being attached to the cradle of the truck, the spring 9 can be also attached to the axle itself if care be taken that the position of the spring be such that it does not interfere with the placing of the load on the truck. At the junction of the free ends of the rod or tube, of which the body of the truck is constructed, at the top end of the cradle portion 3 there is provided a binding member 11 which carries an integral stud 12 adapted to engage the lifting rod 8 at the point where the spring 9 is attached thereto. When the truck is being operated on a level surface, the lifting rod 8 can be secured by the stud 12 in a position in which it does not interfere with the normal operation of the truck. When secured by the stud the lifting rod is held tightly in position by reason of the fact that the spring 9 must be slightly extended in order to permit the engagement of the stud by the rod 8.

The truck according to my invention is completely constructed of metal. The operation of the truck is comparatively simple. When it is desired to lift a heavy ashcan up a flight of stairs the truck is pulled up to the first step in the manner shown in Fig. 4. The operator, without bending, can kick the lifting rod 8 out of engagement with the stud 12 with his foot and then, by exerting pressure on the long end of the lever 7, can place the foot of rod 8 in engagement with the tread of the first step. In so doing the operator necessarily places the spring 9 under considerable tension. After placing the rod 8 in lifting position the operator can then, by a comparatively easy pull, lift the body of the truck with its load to the tread of the

first step. This operation is repeated until the operator arrives at the head of the stairs. The operator can then kick the rod 8 into reengagement with the stud 12 and proceed without impediment along the level surface.

5 This construction offers the important advantage over the construction shown in my aforesaid patent that when the lifting rod is out of operation it is not necessary to keep the spring under full tension whereby the life of the spring is considerably prolonged. Whereas in my prior construction I secured the lifting rod out of position with a separate locking member, I secure the lifting rod 10 in my present construction out of operating position by a slight tension of the spring itself. Moreover, my present construction eliminates the need for brackets arranged on the body of the truck to prevent the free end 15 of the lifting rod from swinging when said rod is out of operative position.

Having thus described the nature and objects of my invention and illustrated a specific embodiment of the same what I claim as 25 new and desire to secure by Letters Patent is:

1. In a handtruck having a frame with an axle at its lower end, a pair of wheels mounted on the axle, a lever connected to the upper part of the frame and a lifting rod having 30 one end connected to the lever and the other end adapted to coact with the tread of a stairway, means for imparting a lifting force to said frame comprising a spring having one end attached to said lifting rod and the other 35 end attached to the body of said truck, and means for securing the said lifting rod out of operating position comprising a stud arranged on the body of said truck and adapted to coact with said rod in such a manner that 40 when the rod is placed in engagement with said stud it is held in that position by the tension of said spring.

2. In a handtruck having a frame with an axle at its lower end, a pair of wheels mounted 45 on the axle, a lever connected to the upper part of the frame and a lifting rod having one end connected to the lever and the other end adapted to coact with the tread of a stairway, a spring having one end attached to a 50 predetermined point on said rod and the other end attached to the frame of said truck near its axle and a stud projecting from the body of said truck at such a point that when the lifting rod is swung into the body of said truck out of operating position it can be 55 placed in engagement with said stud only by placing said spring under a slight tension sufficient to hold said rod in engagement with said stud.

60 3. In a handtruck, in combination, a frame constructed of a single rod bent to form the nose of the truck, the cradle and the handle, the free ends of said rod meeting at a point below the handle of said truck and one of said 65 free ends being turned up to form a stud, a

lever fulcrumed on said stud at a point intermediate one of its ends and its center, and a rod having one of its ends pivoted on the small end of said lever and having its other end adapted to coact with the tread of a stairway, means for exerting a downward pressure on said rod by pressure exerted on the long end of said lever, and means for securing said rod out of operating position under the tension of a spring.

70 75 In testimony whereof I have hereunto set my hand.

80 MARTIN JANKISZ.
